Attorney

UNITED STATES PATENT OFFICE.

CARL SCRABIC, OF URBANA, OHIO.

REPRODUCER FOR TALKING MACHINES.

Application filed June 13, 1919. Serial No. 303,951.

To all whom it may concern:

Be it known that CARL SCRABIC, a citizen of Czechoslovakia, a Republic, residing at Urbana, in the county of Champaign 5 and State of Ohio, has invented certain new and useful Improvements in Reproducers for Talking Machines, of which the following is a specification.

This invention relates broadly to talking 10 machines, and has particular reference to the reproducer structure thereof, the object of the invention being to provide a reproducer of simple and yet efficient construction, capable of being employed with 15 records of standard manufacture and to be of a highly sensitive and accurately balanced character in order that the same may efficiently reproduce all of the sound undulations of a record in a clear, positive and 20 pleasing manner.

To this end, the invention contemplates the provision of a reproducer or sound box wherein is provided a casing having a pair of spaced diaphragms mounted therein, said 25 diaphragms being connected by means of a cross rod with an oscillatory stylus member, the latter being mounted upon knife edges and constructed to carry the usual needle, this construction being such that the vibration 30 of the stylus member will be uniformly and synchronously imparted to the diaphragms so that the latter will vibrate in unison and harmony, whereby the record undulations will be reproduced with marked 35 clarity so that none of the tonal properties thereof will be sacrificed but, on the contrary, will be enlarged and developed in proper varying degrees to render the various shades of tone distinctly audible.

With these and other objects in view, as 40 will appear as the description proceeds, the invention accordingly consists in the novel features of construction, combination of elements and arrangement of parts, herein- 45 after to be fully described and to have the scope thereof pointed out in the appended claim.

In the accompanying drawings, forming a 50 part of this specification, and in which similar characters of reference denote like and corresponding parts:

Figure 1 is a side elevation of a sound box constructed in accordance with the preferred principles of the invention.

Figure 2 is a transverse vertical sectional

view taken through the sound box on the plan disclosed by the line 2—2 of Figure 1.

Figure 3 is an edge elevation of the sound box and disclosing the same as employed for playing the so called "hill and dale" type of record.

Figure 4 is a front elevation of a sound box with the parts positioned as shown in Figure 3.

Referring more particularly to the details 65 of the invention, the sound box 1 comprising the present invention is employed in connection with the usual tone arm 2, the latter is provided with the usual "goose neck" construction 3 upon its forward end 70 or at its point of attachment with the sound box, so that the latter may be readily positioned upon or removed from a record. It will of course be understood that the tone arm may be of any other desired construction 75 and may be associated in any appropriate manner with the amplifying structure (not shown) of a talking machine. The sound box 1 in this instance consists of a main casing 4, which is formed to provide 80 side walls 5, a connecting peripheral wall 6, offset peripheral flanges 7 and an axial bore 8. The latter is in communication with an upstanding internally situated sleeve 9 which has its walls spaced from the side 85 walls 5 of the casing, a space 10 being defined therebetween. Entering this space is the tubular end 11 of the connection 3 and the extent of inward movement of the end 11 into the space 10 is governed by means 90 of an annular collar 12 formed upon the outer wall of the connection 3. To secure the casing 4 in swiveled relation with the connection 3, said casing is provided with an upwardly disposed threaded portion, 95 with which is associated a nut 13, the latter being provided with an annularly and inwardly bent flange 14 which is disposed to cooperate with the collar 12 of the connection 3. By virtue of this construction, 100 it will be manifest that the casing 4 may be revolved about the connection 3 so that the sound box as a whole may be adapted to records of different manufacture. The extent of rotating movement of the sound 105 box is governed by providing, in this instance, the nut 13 with a lug 15, which is disposed to cooperate with fixed stops 16 provided upon the connection 3, said stops being so disposed as to permit the sound 110

box to rotate substantially throughout an arc of ninety degrees. Through the provision of the sleeve 9, the sound box is securely supported for rotatable movement about the connection 3 so that all looseness between parts will be eliminated and in this manner, extraneous vibration reduced.

The flanges 7 of the casing are offset from the side walls 5 to provide diaphragm sockets 17 and in which sockets are located a pair of transversely spaced diaphragms 18 formed from any suitable material. The peripheral edges of the diaphragms are mounted as usual between gaskets 19 and 15 are secured in position by means of clamping rings 20, which are secured to the casing by means of screws or other fastening elements 21. This seating of the diaphragms is of course susceptible to modification, the 20 structure being merely such as to permit the diaphragms to vibrate independently of the sound box structure. Rigidly connected with both of the diaphragms and extending through and beyond the bore 8 is a connecting rod 22 which has its outer ends rigidly 25 secured to the stylus member 23. The member 23 preferably consists of a needle receiving base 24 which is located in vertical alignment with the sleeve 9 and is positioned centrally of the sound box. The base 24 terminates in curvilinear arms 25 which extend around the edges of the sound box and terminate contiguous to the connecting rod 22, to which the ends of said arms are secured. 30 The base 24 is mounted for oscillatory movement upon a pair of knife edges 26 which are resiliently mounted as at 27 in order to place the stylus member under slight pressure so as to eliminate undue vibration or 35 loose play. The base 24 is provided with a 40

needle socket 28^a, in which the usual needle 29 is removably mounted by means of a thumb screw 30.

From the foregoing description, taken in connection with the accompanying drawing, 45 it will be apparent that there is provided a sound box of considerable utility and one particularly capable of carrying out the objects of the invention. The sound box essentially is so constructed that the stylus member 50 will have its point of oscillation spaced equidistantly from the diaphragms 18, so that the movement of the stylus member will be equally imparted to the diaphragms so that the sound waves created thereby will be of equal proportions. This structure is believed to be in contra-distinction to the method hitherto employed of locating the pivot point of the stylus member to one side 55 of the diaphragms and has overcome the 60 disadvantage found in the latter of creating different and foreign vibrations in the spaced diaphragms.

I claim:

In a sound box for talking machines, a 65 casing comprising a pair of transversely spaced walls, a sound conduit extending axially of said sound box and connecting said walls, a sleeve projecting upwardly from said conduit and disposed between said 70 walls, a tone arm connection including a vertically disposed tube having its lower end telescoped between said walls and sleeve, a collar provided on said tube, and a retaining ring connected with said casing and disposed to engage with said collar to effect a 75 rotatable connection between said sound box and tube.

In testimony whereof I affix my signature.
CARL SCRABIC.
